ACETATE LUNCH PLACE MAT

Filed May 20, 1941

Inventor,
Arthur Moos

UNITED STATES PATENT OFFICE

130,408

DESIGN FOR AN ACETATE LUNCH PLACE MAT

Arthur Moos, Bellmore, N. Y.

Application May 20, 1941, Serial No. 101,032

Term of patent 3½ years

To all whom it may concern:

Be it known that I, Arthur Moos, a citizen of the United States, residing at Bellmore, Long Island, in the county of Nassau and State of New York, have invented a new, original, and ornamental Design for Acetate Lunch Place Mats, of which the following is a specification, reference being had to the accompanying drawing, forming part thereof.

The figure is a plan view of an acetate lunch place mat, showing my new design.

I claim:

The ornamental design for an acetate lunch place mat, as shown.

ARTHUR MOOS.
